CLAIM

The ornamental design for a bowl assembly including a bowl and a lid, as shown and described.

DESCRIPTION

FIG. 1 is a top perspective view of a first embodiment of a bowl assembly including a bowl and a lid;

FIG. 2 is a front elevation view of FIG. 1, wherein each of a rear elevation view, a left side elevation view and a right side elevation view is identical to the image of FIG. 2;

FIG. 3 is a top plan view of FIG. 1;

FIG. 4 is a bottom plan view of FIG. 1;

FIG. 5 is a bottom perspective view of FIG. 1;

FIG. 6 is a top perspective view of a second embodiment of a bowl assembly including a bowl and a lid;

FIG. 7 is a front elevation view of FIG. 6, wherein each of a rear elevation view, a left side elevation view and a right side elevation view is identical to the image of FIG. 7;

FIG. 8 is a top plan view of FIG. 6;

FIG. 9 is a bottom plan view of FIG. 6;

FIG. 10 is a bottom perspective view of FIG. 6;

FIG. 11 is a top perspective view of a third embodiment of a bowl assembly including a bowl and a lid;

FIG. 12 is a front elevation view of FIG. 11, wherein each of a rear elevation view, a left side elevation view and a right side elevation view is identical to the image of FIG. 12;

FIG. 13 is a top plan view of FIG. 11;

FIG. 14 is a bottom plan view of FIG. 11; and,

FIG. 15 is a bottom perspective view of FIG. 11.

The stipple fill represents a surface texture provided on a portion of the bowl of each bowl assembly including a bowl and a lid on which it is depicted.
